DESIGN FOR A DRESS

Louis J. Richard, New York, N. Y.

Application September 2, 1937, Serial No. 71,420

Term of patent 3½ years

To all whom it may concern:

Be it known that I, Louis J. Richard, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein

I claim:

The ornamental design for a dress, substantially as shown and described.

LOUIS J. RICHARD.
